UNITED STATES PATENT OFFICE

LEONARD DE WIT, OF CHICAGO, ILLINOIS, ASSIGNOR TO MOORE BROS., OF JOLET,
ILLINOIS, A CORPORATION OF ILLINOIS

DESIGN FOR A GAS OR ELECTRIC RANGE OR ANALOGOUS ARTICLE

Application filed April 15, 1931. Serial No. 39,494. Term of patent 7 years.

To all whom it may concern:

Be it known that I, LEONARD DE WIT, a citizen of the United States, and resident of Chicago, in the county of Cook, and State of Illinois, have invented a new, original, and ornamental Design for a Gas or Electric Range or Analogous Article, of which the following is a specification, reference being had to the accompanying drawings, forming a part thereof.

In the drawings:

Fig. 1 is a front perspective view of the range showing my new design with the cover folded down;

Fig. 2 is a similar front perspective view with the cover in the raised position;

Fig. 3 is a plan view of the range on a larger scale, and

Fig. 4 is a front elevational view thereof.

The body of the range is flat at the back, as indicated at 4, and bulges out into the front wall 5, as indicated at 6.

I claim:

The ornamental design for a gas or electric range or analogous article as shown and described.

In witness whereof, I hereunto subscribe my name this 11th day of April, 1931.

LEONARD DE WIT.
